BRAKE DRUM

Frank H. Lejeune, Detroit, Mich., assignor to
 Kelsey-Hayes Wheel Corporation, Detroit,
 Mich., a corporation of New York

Application April 11, 1932. Serial No. 604,550

11 Claims. (Cl. 188—218)

The invention relates to brake drums and refers more particularly to brake drums for use with motor vehicles wheels. One of the objects of the invention is to provide an improved construction of brake drum having a floating brake engaging member. Other objects are to provide an improved construction for connecting the brake engaging member to the body of the brake drum and to provide an improved method of assembly.

These and other objects of the invention will become apparent from the following description, taken in connection with the accompanying drawings, in which

15 Figure 1 is an elevation of a brake drum showing an embodiment of my invention;

Figures 2 and 3 are cross sections on the lines 2—2 and 3—3, respectively, of Figure 1;

20 Figures 4 and 5 are views similar to Figure 2, showing other embodiments of my invention;

Figure 6 is a view similar to Figure 1, showing another embodiment of my invention;

Figure 7 is a cross section on the line 7—7 of Figure 6;

25 Figure 8 is a view similar to Figure 7 showing another embodiment of my invention.

As shown in Figures 1, and 2 and 3, the brake drum comprises the body 1 and the brake engaging member 2, the body being formed of sheet metal and, more particularly, sheet steel and stamped or drawn to shape and the brake engaging member being formed of cast iron, and, more particularly, being centrifugally cast. The body 1 has the web 3 and the peripheral annular flange 4 which is provided at its free edge with the peripherally spaced barrel portions 5. The centrifugally cast brake engaging member has the inner cylindrical brake engaging face 6 and extends within the annular flange 4 and has intermediate its edges and substantially midway of its width the radially outwardly extending peripherally spaced projections 7 which fit between the barrel portions 5. 8 is a wire ring extending through and rotatably mounted in the barrel portions 5 and having its portions intermediate these barrel portions imbedded in and molecularly bonded to the projections 7. The ends of this wire ring preferably extend adjacent to each other and are so located that they are imbedded in one of these projections 7.

50 In forming this brake drum, the body 1 is formed by suitable stamping or drawing operations and its barrel portions are crimped about the wire ring. This body is then placed in a suitable revoluble fixture which also has portions ex-

tending beyond the free edge of the annular flange to form the outer face of the brake engaging member beyond this annular flange. The fixture with the body in place is rotated and during the rotation the molten metal is poured and 60 centrifugally cast. The centrifugal casting is accomplished without fusing or molecular bonding of the brake engaging member to the annular flange and its barrel portions and this may be accomplished by controlling the relative temperatures or by a suitable protective coating upon the portions of the annular flange and its barrel portions with which the molten metal comes into contact. However, the brake engaging member fuses with and is molecularly bonded to the wire 65 ring 8.

With this arrangement, it will be noted that the annular brake engaging member 2 is connected to the brake drum body and, more particularly, the annular flange of this body, so that the brake 70 engaging member may move relative to the brake drum body without distorting the latter during the operation.

In the modifications shown in Figures 4 and 5, the annular brake engaging members are preferably formed separately from the brake drum bodies. These brake engaging members are preferably centrifugally cast and then assembled with the brake drum bodies by connecting the two together. As shown in Figure 4, the sheet steel 75 brake drum body 9 has the web 10 and the peripheral annular flange 11 which is formed with peripherally spaced tongues at its free edge. The annular centrifugally cast brake engaging member 12 is provided intermediate its edges and preferably midway thereof with the radially outwardly extending peripherally spaced projections 13 which are adapted to fit between the tongues at the free edge of the annular flange 11. When centrifugally casting this annular brake engaging member, the projections 13 are cast about and molecularly bonded with the wire ring 14 and one of the projections is cast about the adjacent ends of this wire ring. The brake engaging member is assembled with the brake drum body 100 by inserting the former into the latter and then by bending over the tongues at the free edge of the annular flange to form the barrel portions 15, these tongues being bent radially outwardly and toward the main portion of the annular flange. 105 As shown in Figure 5, the arrangement of parts and also the method of assembly is in general the same as that disclosed in connection with Figure 4, with the exception that the peripherally spaced tongues at the free edge of the annular flange 16 110

of the brake drum body are bent radially inwardly and toward the main portion of the annular flange and around the wire ring 17 to thereby connect the annular brake engaging member to the 5 brake drum body.

As shown in Figures 6 and 7, the brake drum body comprises the stamped web 18 which is provided at its periphery with the peripherally spaced barrel portions 19 extending around the 10 wire ring 20. The annular brake engaging member 21 has at its edge adjacent to the web 18 the peripherally spaced projections 22 for fitting between the projections 19 and these projections 22 are cast around and molecularly bonded to the 15 portions of the wire ring between the projections 19. The brake engaging member 21 is preferably formed by centrifugally casting the same in place and around the wire ring 20 with the latter extending through the barrel portions 22.

Figure 8 discloses another modification in which the brake drum comprises the sheet steel web 23 preferably formed by a stamping operation and the sheet steel annular flange 24 preferably formed by rolling the same and also the annular brake engaging member 25 which is preferably a liner of cast iron centrifugally cast into the annular flange and fused or molecularly bonded thereto. The annular flange 24 is connected to the web 23 by means of the wire ring 26 which extends through the annular series of alternate 25 barrel portions formed upon the web and the laterally extending portion or back 27 of the 30 annular flange.

What I claim as my invention is:

- 35 1. A brake drum, comprising a body, an annular member connected to said body and an annular brake engaging member molecularly bonded to said annular member.
- 40 2. A brake drum, comprising a body, an annular member connected to said body and an annular brake engaging member cast upon said annular member.
- 45 3. A brake drum, comprising a body, a wire ring connected to said body and an annular brake engaging member molecularly bonded to said wire ring.

75

4. A brake drum, comprising a body, a wire ring connected to said body and an annular brake engaging member cast upon said wire ring.

5. A brake drum, comprising an annular flange having peripherally spaced barrel portions, a wire 80 ring extending through said barrel portions and a brake engaging member having portions between said barrel portions engaging said wire ring.

6. A brake drum, comprising a body having 85 peripherally spaced barrel portions, a wire ring extending through said barrel portions and a brake engaging member having portions between said barrel portions engaging said wire ring.

7. A brake drum, comprising a web having 90 peripherally spaced barrel portions, a wire ring extending through said barrel portions and a brake engaging member having portions between said barrel portions engaging said wire ring.

8. A brake drum, comprising a body, an annular brake engaging member and an annular member 95 extending alternately through said body and member for connecting the same to each other.

9. A brake drum, comprising a body member, an annular brake engaging member and an annular member 100 for connecting said first mentioned members to each other, one of said first mentioned members having portions crimped over said annular member for securing the latter to the former.

10. A brake drum, comprising a web, an annular brake engaging member and an annular member 105 extending alternately through said web and brake engaging member for connecting the same to each other.

11. A brake drum, comprising a web member, an annular flange member, an annular member 110 for connecting said first mentioned members to each other, one of said first mentioned members having barrel portions through which said annular member extends, and a liner upon said flange member.

FRANK H. LEJEUNE.
